UNITED STATES PATENT OFFICE.

THEODORE W. FOSTER, OF PROVIDENCE, RHODE ISLAND.

DESIGN FOR A COVER FOR PUFF-BOXES.

SPECIFICATION forming part of Design No. 28,527, dated May 3, 1898.

Application filed March 31, 1898. Serial No. 676,003. Term of patent 7 years.

To all whom it may concern:

Be it known that I, THEODORE W. FOSTER, of Providence, in the county of Providence and State of Rhode Island, have invented and 5 produced a new and original Design for the Covers of Puff-Boxes and Similar Toilet Articles, of which the following is a specification, reference being had to the accompanying drawing, forming part thereof.

10 The drawing is a top view of the circular cover of a puff-box, showing my design.

The leading and material feature of my design consists in the raised circular ornamentation inclosing the representation of two 15 nymphs, the said circular ornamentation being of less diameter than the circular cover and placed on one side of the cover.

In the drawing, 2 indicates an ornament placed on one side of the cover, consisting of 20 three radially-disposed strings of graduated beads; 3, two branches of foliated scrolls extending from the ornament 2 along a section of the circular margin of the cover; 4, 4,

two raised beads terminating in scrolled ends, provided with two strings of graduated beads 25 along the upper half of their inner side and inclosing a practically circular space of less diameter than the circular cover. From the raised beads 4, extend tangentially ornamental leaves. Two winged nymphs, terminating in foliations, extend along the inner side of the lower part of the raised beads 4, 30 the bodies of the nymphs curving toward the center of the cover.

Having thus described my invention, what 35 I claim as new, and desire to secure by Letters Patent, is—

The design for the cover of a puff-box or similar article herein shown and described.

In witness whereof I have hereunto set my 40 hand.

THEODORE W. FOSTER.
